ATTY.

UNITED STATES PATENT OFFICE.

EDWIN L. ROBINSON, OF NORTH ATTLEBORO, MASSACHUSETTS.

SNAP-HOOK FOR WATCH-CHAINS.

No. 856,913.

Specification of Letters Patent.

Patented June 11, 1907.

Application filed March 9, 1904. Serial No. 197,849.

To all whom it may concern:

Be it known that I, EDWIN L. ROBINSON, a citizen of the United States, residing at North Attleboro, in the county of Bristol and State of Massachusetts, have invented a new and useful Improvement in Snap-Hooks for Watch-Chains, of which the following is a specification.

The nature of my invention consists in the improved construction of the spring-means, for closing the opening of the hook, as hereinafter set forth.

In the accompanying drawings:—Figure 1 represents a side view of a snap hook for watch chains embodying my invention. Fig. 2 represents a longitudinal section of the same. Fig. 3 represents an axial section of the hollow head. Fig. 4 represents the preferred form of the wire blank from which the hook and the tongue are made. Fig. 5 shows the same when the ends are folded together for insertion into the cavity of the head. Fig. 6 shows a modification in the form of the hook. Fig. 7 represents an enlarged section taken in the line 7 7, of Fig. 4.

In the drawing, *a* represents the hollow ornamental head, provided with a large and a small end, and to the small end is soldered the ring *b*. The hook *c* and the tongue *d* may be formed from a blank *e*, of half round wire, swaged at the portions *ff*, to the requisite thickness for securing the required spring action in the shank *j* of the hook *c*, and also of the tongue *d*, the semi-cylindrical end portions *g g* of the said blank which are thicker than the spring portion being provided with the transverse peripheral groove *h*.

In putting the parts together, the blank *e* when bent up, as shown in Fig. 5, is to be inserted into the cavity of the head *a*, at its larger end, so that the swaged portions *ff*, will be covered in the hollow of the head, and then the wall of the said head at its smaller clasping end is to be pressed into the peripheral groove *h*, as shown in Fig. 2, and thereafter the cut *i* is to be made, which serves to separate the portion *c*, which forms the hook, from the portion *d*, which forms the tongue.

50 The preferred form of construction is shown in Figs. 2 and 5, in which both the hook *c*, and the tongue *d* are provided with a

spring shank *f*, but the hook *c* may be made without the spring shank as shown in Fig. 6, in carrying out my invention.

Instead of forming up the hook and tongue from a blank in one piece of stock, they may be formed in separate pieces, and then placed together within the cavity of the head and secured therein as shown in Fig. 2.

I claim as my invention:

1. In a snap hook for watch chains, the combination of the hook swaged at the side of its shank to form a spring, and having an end portion thicker than the spring part, and the separate tongue swaged at the side of its shank to form a spring, and also having an end portion thicker than the spring part, with a hollow ornamental head, provided with a small end which serves to clasp the thick end portions of the shanks of the hook and tongue firmly together, the said shanks being inclosed in the hollow of the head.

2. In a snap hook for watch chains, the combination of the hook, and a separate tongue swaged at the side of its shank to form a spring, and having an end portion thicker than the spring part, with a hollow ornamental head, provided with a small end which serves to clasp the end portion of the shank of the tongue firmly to the end portion of the shank of the hook, the said shanks being inclosed in the hollow of the head.

3. In a snap hook for watch chains, the combination of the hook provided with a transverse groove at the end of its shank, and a separate tongue swaged at the side of its shank to form a spring, and having an end portion thicker than the spring part, and provided with a transverse groove, with a hollow ornamental head, provided with a small end which serves to clasp the thick end portion of the shank of the tongue firmly to the end portion of the shank of the hook, and having the clasping end of the ornamental head swaged into the transverse grooves of the hook and tongue, the said shank of the tongue being inclosed in the hollow of the head.

EDWIN L. ROBINSON.
